UNITED STATES PATENT OFFICE

FRANK B. DAVIDSON AND WILLIAM GORGES, OF MARSEILLES, ILLINOIS, ASSIGNEES TO HOWE AND DAVIDSON COMPANY, OF EAST ORANGE, NEW JERSEY, A CORPORATION OF NEW JERSEY.

PAPER-COATING MACHINE.

No. 890,221.

Specification of Letters Patent.

Patented June 9, 1908.

Application filed November 5, 1906. Serial No. 342,089.

To all whom it may concern:

Be it known that we, FRANK B. DAVIDSON and WILLIAM GORGES, citizens of the United States, both of Marseilles, in the county of 5 Lasalle and State of Illinois, have invented certain new and useful Improvements in Paper-Coating Machines; and we do hereby declare that the following is a full, clear, and exact description thereof, reference being 10 had to the accompanying drawings, and to the letters of reference marked thereon, which form a part of this specification.

This invention relates to a machine for coating paper or other sheet material with 15 paraffin, or the like, of the same general character as that set forth in Patent No. 437,435, granted September 30th, 1890 to Warren B. Howe.

A machine embodying our invention is 20 more especially intended for use in coating paper in a continuous web as it comes from the paper making machine, but the features of construction constituting our invention may be also applied to a form of machine 25 employed for coating separate sheets of paper or straw-board, as in the case of the machine shown in said Howe patent.

The object of our invention is to improve 30 the construction of paper coating machines of the kind referred to with respect to various features of the same, and it consists in the matters hereinafter set forth and pointed out in the appended claims.

As illustrated in the accompanying drawings:—Figure 1 is a view in side elevation, with parts in section of a machine embodying our invention. Fig. 2 is a cross-sectional view of the same, taken upon line 2—2 of Fig. 1. Fig. 3 is an end view of the same, as 35 viewed from the right hand of Fig. 1, with parts in section. Fig. 4 is an end view of the machine, as viewed from left hand of Fig. 1. Fig. 5 is an end view like Fig. 4 showing some of the moving parts in changed position and certain parts in section. Fig. 6 is 40 a horizontal plan section, taken upon the line 6—6 of Fig. 1. Fig. 7 is an enlarged detail plan section, taken on line 7—7 of Fig. 1. Fig. 8 is an enlarged detail section, taken 45 upon line 8—8 of Fig. 7. Fig. 9 is a detail plan view of the upper roll and upper reservoir of the machine, with adjacent parts. Fig. 10 is an enlarged detail section, taken 50 upon line 10—10 of Fig. 9. Fig. 11 is a de-

tail perspective view of one end of the upper 55 reservoir. Fig. 12 is an enlarged perspective view of one end of the longitudinal bar or girder which carries the adjusting means for the upper reservoir. Fig. 13 is a detail side elevation of the mechanism for lifting the 60 upper roll. Fig. 14 is a detail section, taken upon line 14—14 of Fig. 13. Fig. 15 is a detail section, taken upon line 15—15 of Fig. 13. Fig. 16 is an enlarged detail section taken through the bearings of the upper and 65 lower rolls, and the adjustable support for the upper roll interposed between said bearings. Fig. 17 is a detail section, taken upon line 17—17 of Fig. 16. Fig. 18 is a plan view of the main trough or receptacle with parts 70 broken. Fig. 19 is a detail plan view of one end of the feed regulator for the lower roll, with its adjustable support. Fig. 20 is a detail cross-section, taken on line 20—20 of Fig. 19. Fig. 21 is a detail plan view of one 75 end of the scraper for the lower roll and its adjusting means. Fig. 22 is a section, taken on line 22—22 of Fig. 21. Fig. 23 is a detail plan view of one end of the scraper for the upper roll, with its adjusting means. Fig. 80 24 is a section taken upon line 24—24 of Fig. 23.

As shown in said drawings, A A¹ indicate two upright frame standards located at opposite ends of the machine, and B an elongated, shallow trough or receptacle for paraffin or other coating material. Said trough is made of cast metal and extends between and is attached at its ends to the upper ends of the frame uprights A A¹; constituting 85 90 with the latter the main frame of the machine.

C indicates the lower and D the upper roll for applying the coating material to the paper, said rolls being arranged longitudinally above the receptacle B, with their central axes in the same vertical plane. The lower roll C is mounted at its ends in stationary bearings A² A³ which are secured to and rise from the upper ends of the frame standards A A¹. The upper roll D is mounted at 95 its ends in bearings carried by transversely extending, horizontally arranged, pivoted, supporting members or arms E E¹ which are connected by means of pivots e e¹ with brackets A⁴ A⁵ that are attached to and rise from 100 the upper ends of the standards A A¹. The 105 said pivots e e¹ are located at one side of the

axes of the rolls C and D, so that rising and falling movement of the upper roll is afforded by the swinging of said arms on said pivots.

The frame standards A A¹ are provided 5 near their upper ends at some distances below their top surfaces with inwardly extending, horizontal shelves a a¹ (Fig. 1) on which the ends of the receptacle B rests and to which the same is bolted. Said standards 10 A A¹ are, moreover, provided with flat horizontal top surfaces to which the bearings A² A³ for the lower roll, and the brackets A⁴ A⁵ for sustaining the upper roll are bolted, and said horizontal top surfaces of the standards 15 are surrounded by raised rims a² a³ (Fig. 1) forming receptacles for lubricating material that may escape from the bearings located above said frame standards.

Extending horizontally beneath the receptacle B is a steam chamber B¹, the top wall of which constitutes the bottom wall of the receptacle so that heat will readily be communicated to the contents of the receptacle, in order to retain the coating liquid, usually 20 melted paraffin, in its liquid condition and at a desired uniform temperature. Said steam chamber B¹ is preferably cast integral with the receptacle. Said steam chamber B¹ is provided with a supply pipe b and return pipe b¹. Steam is supplied to the supply pipe b from a suitable steam generator and, after circulating through the chamber B¹, passes therefrom through the outlet pipe b¹. Said steam chamber preferably extends the 25 full width of the receptacle B and nearly the entire length thereof and is provided with transverse partitions b² b² (Fig. 18) extending alternately from opposite sides of the chamber so as to form a tortuous passage 30 through which the steam passes from the inlet pipe b to the outlet pipe b¹, which pipes are connected with opposite ends of said tortuous passage.

On the shaft or journal of the lower roll C, 45 exterior to its bearing A³, is secured a gear wheel C¹ which intermeshes with a like gear wheel D¹ secured to the journal of the upper roll D. On a bracket A⁶ is mounted a driving shaft I which is given motion from any 50 suitable source of power and has attached to it a gear pinion I¹ which intermeshes with the gear wheel C¹ of the lower roll. By the gearing described, the rolls C and D are driven so that they rotate in opposite directions at the same rate of speed.

The lower roll C extends downwardly into the receptacle B and its lower portion is immersed in the coating liquid contained in said receptacle, which is taken up by the said 55 lower roll, by which it is transferred to the under side of the sheet. The upper roll D applies the coating liquid to the upper side of the sheet and receives its supply of paraffin from a longitudinal trough or reservoir F 60 which is mounted at one side of the said up-

per roll and is supported on the arms E E¹ by which said upper roll is directly sustained. Said reservoir F is located at the downwardly moving side of the roll D, and is of approximately L-shape in cross-section, having the margin of its lower wall closely adjacent to the surface of the said roll. The upright side wall of said reservoir forms one side of a trough extending longitudinally of the roll D, the other side of which is formed by the surface of the roll itself in its part above the said bottom wall. Said reservoir F is provided with end walls f f, the margins of which, adjacent to the roll D, are curved to conform to the curvature of the roll and are in close contact with the same, to prevent the escape of the coating liquid at the ends of the reservoir. The ends of the supporting arms E E¹ are extended beyond the roll D at the sides thereof at which the reservoir is located, and said reservoir is supported on said arms by means of longitudinally extending arms F¹ F¹ on the ends of the reservoir which extend and are bolted to the said arms E E¹. Liquid from the reservoir F is fed to the 70 downwardly moving sides of the roll D through a narrow space or opening afforded between the margin of the bottom wall of said reservoir and the adjacent surface of the roll. In order that the feed of liquid to 75 said roll D may be exactly adjusted to give a coating of desired thickness to the paper, and in order that the quantity of liquid fed to the roll shall be uniform throughout the entire 80 length of the same, provision is made for adjusting the inner margins of the bottom wall of the reservoir relatively to the surface of the said roll as follows:

G indicates a rigid bar or girder which extends longitudinally of the reservoir F outside of and parallel with the same, and the ends of which are rigidly attached to the ends of the supporting arms E E¹. Said bar G, as shown in Figs. 10 and 12, consists of a vertically extending web portion g, provided between its upper and lower margins with an outwardly extending, horizontal, stiffening flange g¹. At its ends the said bar G is shown as provided with horizontal inwardly extending lugs g² g² which are arranged in overlapping relation with like lugs f¹ on the arms F¹ of the reservoir F and laterally extending lugs e² e² on the levers E and E¹; said lugs e² g² and f¹ being provided with coinciding bolt holes through which are inserted bolts (Fig. 8) by which both the reservoir F and the bar G are secured to the ends of the said arms E E¹. A plurality of adjusting screws H H¹ (Figs. 10 and 12) extend horizontally through the bar G; the screws H having screw-threaded engagement at their inner ends with the bottom wall of the reservoir and turning freely in the said bar, while the screws H¹, which are arranged alternately with the screws H, have screw- 100 105 110 115 120 125 130

threaded engagement with the bar and abut at their inner ends against the trough or reservoir. The screws H and H¹ are arranged at close intervals throughout the entire 5 length of the reservoir and by adjustment of the same the bottom wall of the said reservoir may be exactly and accurately held parallel with and at a desired distance from the downwardly moving surface of the upper 10 roll D.

Provision is made for affording a continuous feed or supply of the liquid paraffin or coating material to the receptacle B and reservoir F by means as follows: J is a supply 15 tank, shown as resting upon the floor between the standards A A¹, and K a pump attached to the standard A¹ and provided with an inlet pipe L which passes over the end wall of the tank J and extends downwardly 20 therein to a point near its bottom. The pipe L has a branch j provided with a valve j¹ and connected with an outlet opening at the bottom of the tank. The pump plunger k is operated by a connecting rod k¹ from a 25 gear pinion K¹ mounted on the bracket A⁶ and intermeshing with the driving pinion I¹; the upper end of said connecting rod k¹ being engaged with a wrist pin k² on the gear pinion K¹. A delivery pipe L¹ leads from 30 the said pump and rises to a point above the upper reservoir F, the upper end of said pipe being extended horizontally to the adjacent end of said reservoir and directed downwardly so as to discharge into the same. 35 An overflow pipe L² extends through the bottom wall of said receptacle B and has its open upper end located at the level of the surface of the liquid in said receptacle, the lower end of said pipe discharging into the 40 tank J. An overflow pipe L³ is connected with the side wall of the reservoir F at the opposite end of the same from the delivery pipe L¹. Said overflow pipe L³ leads downwardly to and discharges into the main 45 trough or receptacle B. The liquid paraffin is supplied continuously to said reservoir F by the pump, the surplus liquid passes therefrom back to the receptacle B through the overflow pipe L³, and the overflow from the 50 latter receptacle passes continuously therefrom to the tank J through the overflow pipe L². The liquid paraffin is continuously heated by passing through steam-heated receptacle B, and is thereby maintained at a 55 desired temperature.

As hereinbefore stated, the arms E E¹, that support the upper roll D and the reservoir F thereof, are connected by pivots e e¹ with the machine frame, and in the preferred 60 embodiment of my invention illustrated, the said supporting arms E E¹ are extended outwardly beyond the said pivots e e¹ and with the outer ends thereof are connected devices by which said outer ends of the levers may 65 be depressed and the inner ends thereof, with

the upper roll supported thereby, lifted to separate the rolls from each other; the arms thus arranged having the form and function of levers.

The distance apart of the rolls, or the approach of the movable upper roll towards the lower stationary one, is determined or limited by means of adjusting means interposed between the arms E E¹ and the top surfaces of the bearings A² A³ of the lower roll. Each 75 of such adjusting devices consists, as clearly seen in Figs. 4, 16 and 17, of a horizontally arranged, tapered or wedge-shaped block M interposed between opposite inclined upwardly and downwardly facing bearing surfaces m m¹ formed on said bearings and arms. To provide for moving or shifting the block M and holding the same in adjusted position, an adjusting screw M¹, engaged with the wedge block and arranged to give endwise 80 movement thereto, is employed. In the particular construction shown, the adjusting screw M has screw-threaded engagement with a lug m² which rises from the bearing of the lower roll and is engaged with the block 85 by a connection permitting the turning of the screw while producing endwise movement of the block with the screw. In the particular construction illustrated in the drawings, the screw M¹ has near its inner end an annular 90 groove and the block is provided with a recess and with a vertical slot opening from the end surface of the wedge into said recess; the groove in the screw being engaged with the metal at the sides of said slot, so that the 95 screw is held from endwise movement relatively to the block but is free to rotate by the turning of its grooved end in said slot.

In order to hold the wedge block in place between the arm and the bearing of the lower 10 roll, said block is provided on its top and bottom surfaces with longitudinal ribs m³ m⁴ (Fig. 17) adapted to engage corresponding 11 grooves formed in the bearing faces m m¹ of said arm and bearing. By adjustment endwise of the wedge blocks arranged as described, both ends of the upper roll C may be 12 adjusted toward and from the lower roll and the rolls thereby brought accurately into parallel relation and exactly adjusted with respect to their distance apart, according to 13 the thickness of the paper being coated and the pressure that it is found desirable to apply to the paper.

It sometimes occurs, in a machine constructed as above described, that the weight of the upper roll and parts carried by the arms E and E¹ is not sufficient to produce the desired pressure upon the paper, and we have therefore provided, in the machine shown in 1 the accompanying drawings, means for applying a downward stress or pressure to ends of the upper roll D. Devices for this purpose are shown in the accompanying drawings as follows: To each of the arms E E¹, at

a point near the journal of the upper roll and preferably at the side of said journal remote from or opposite the pivot of the arm is pivoted the upper end of a vertical connecting rod N, the lower end of which is pivoted to a horizontal lever N¹, mounted to swing in a vertical plane at the inner face of the adjacent frame standard A or A¹. The connecting rod N is pivoted to said lever N¹ by a pivot n located near the fulcrum pivot n¹ of said lever. To the end of said lever N¹ remote from its fulcrum pivot is pivoted the upper end of an upright connecting rod N², which, at its lower end, is connected by a pivot n² with a second lever N³ located below and parallel with the lever N¹, the pivot n² being located near the fulcrum pivot n³ of said lever N³. The connecting rod N² is provided with a weight N⁴, preferably hung on the lever so as to be movable thereon. Said weight N⁴ operates through the levers N¹ N³ to exert a downward pull on the arm E or E¹ with which it is connected, which, by reason of the interposition of the levers, will be much greater than the downward pressure due to the gravity of the weight itself. By the construction described, therefore, the upper roll, while capable of being lifted, is held during the operation of the machine by the weight and compound levers described, at a fixed distance from the lower roll, determined by the adjustment of the wedge blocks M¹ M¹.

Provision is made for lifting the upper roll when necessary as follows: O is a rock-shaft extending longitudinally of the machine below the outer ends of the arms E E¹ and mounted in brackets o⁴ o⁴ secured to the side faces of the frame standards A A¹. Said rock-shaft O is provided with eccentrics O¹ O¹ adapted to engage upwardly facing surfaces formed on yoke pieces P¹ which are attached to the lower ends of upright rods P, the upper ends of which are engaged with the said outer ends of the arms E E¹, preferably by means of loops on the upper ends of the rods engaging notches in the upper edges of said arms. The rods P P are shown as engaged at points between their ends with guide lugs o³ projecting from the upper ends of the frame standards. Each yoke piece P¹, as clearly shown in Figs. 13" and 15, is provided with two depending parallel arms that extend at opposite sides of the rock-shaft and which are provided at their lower ends with laterally projecting lugs p p, the upper margins of which are provided with notches or recesses forming seats for the ends of a bearing plate p¹ which extends beneath and bears against the under surface of the eccentric O¹. Set-screws p² p², threaded upwardly through the lugs p p act against the lower surface of the bearing plate p¹ at the ends of the same, thereby affording vertical adjustment of the said plate on the yoke pieces.

Attached to the rock-shaft O at one end of the same is a crank arm or operating lever O², which preferably extends downwardly to a point near the floor so that it may be operated by the foot.

For locking or holding the upper roll D at a desired elevation when lifted by the device described, we provide means as follows: Attached to the rock-shaft O is a notched wheel or disk O³, the notches of which are adapted to be engaged by a vertically moving or sliding detent Q located beneath said disk. Said detent Q is mounted on the upper end of a vertically sliding rod Q¹ mounted in vertically separated guide brackets a⁴ a⁵ on the frame standard A. An expansively acting coiled spring Q², interposed between the lowermost guide bracket a⁶ and a collar q on the rod Q¹, exerts upward pressure on said rod adapted to retain the detent Q normally elevated and in engagement with the notched wheel O³. For operating said detent the lower end of the rod Q¹ is extended downwardly to a point near the floor and is pivotally connected with a lever arm R¹ attached to a rock-shaft R which is mounted in bearings at the lower part of the standard A and is provided at the outer face of said standard with a foot lever R² which, when depressed, effects the release of the detent Q from the notched wheel O³ and thus leaves the rock-shaft free to turn.

In order to regulate the quantity of coating material taken up by the lower roll C and applied to the lower surface of the paper, as required to give the paper a coating of the desired thickness, a feed regulating roll S is arranged at the upwardly moving side of the said roll C. Said roll S is mounted in bearings permitting it to freely turn, and is held or pressed against said roll C, so that it is turned or revolved by its frictional contact with the same. Said roll S is provided with a covering S¹ of felt, cloth or other like material, which, by its pressure against the surface of the roll C, serves to limit the quantity of liquid which is carried by the said roll to and deposited upon the paper. Said roll S, as shown in the drawings, consists of a cylindric tube or pipe of considerable diameter and thickness in order that it may have suitable stiffness. To provide for adjustment of the roll S toward and from the roll C, so that it may be made to bear with a desired degree of pressure against said roll C, the said roll S has at each end a journal adapted to turn in the upper end of the upright arm of an L-shaped supporting lever S² which is pivoted to the machine frame by a pivot s located at the junction of the upright and horizontal arms of said lever, and so arranged that the upper ends of the upright arm, with the end of the bar S carried thereby, will swing horizontally toward and from the lower roll C when the lever is turned on

its said pivot. Said lever S^2 is pivoted to a bracket A^7 bolted to the top surface of one of the frame standards A or A^1 . The horizontal or adjusting arm of the supporting lever S^2 extends outwardly from the pivot s of the lever and the bracket A^7 is also extended horizontally outward from said pivot s and is provided (as more clearly shown in the detail views of Figs. 19 and 20), with a laterally extending lug s^1 located beneath the said horizontal arm of the supporting lever. In the said lugs s^1 is rigidly secured an upright screw-threaded adjusting bolt S^3 which rises through an aperture in the outer ends of the said horizontal arm of the supporting lever. On said adjusting bolt, above and below the lever arm, are located adjusting nuts s^2 s^3 . The top and bottom surfaces of said adjusting arm, in its part engaged by the said nuts, is made of rounded or convex form so that the nuts will have proper bearing against the arm, notwithstanding the change in the angular position of the same occurring in its adjustment. By adjusting the nuts s^2 s^3 on the bolt S^3 , at both ends of the machine, the roll may be held against the roll C with a degree of pressure required for giving proper supply or feed of the coating material to the paper.

The rolls C and D are provided with cleaning scrapers having scraping blades in contact with the rolls for scraping off or removing any particles of fiber or other foreign material that may be transferred from the paper to said rolls. In the case of the lower roll, its scraper is located at the downwardly moving side of the roll so as to remove any particles adhering to the surface of the roll before the same enters the liquid in the receptacle B , and in the case of the upper roll, its scraper is located at the upwardly moving side of said roll so as to likewise remove any particles from the surface of said roll before the latter reaches the liquid in the upper reservoir F . The scraper for the upper roll consists of a bar U provided with a scraping blade u , while the scraper for the lower roll consists of a like bar T provided with a scraping blade t . The blades t and u are arranged obliquely to the surfaces of the rolls C and D , so that, by the angular or rotative adjustment of the bars T and U , to which they are attached, the edges of the blades will be pressed with more or less force against the surfaces of the rolls. The mountings for the two scrapers, by which they are adjustably supported, are provided with means affording such rotative adjustment of said scrapers. The lower scraper is mounted on the frame of the machine while the upper scraper is mounted on the supporting arms E E^1 of the upper roll. In the case of the lower scraper, the supporting bar T thereof is provided at its ends with journals which

engage bearing apertures formed in brackets 65 T^1 T^1 attached to the inner faces of the brackets A^4 A^5 , and said bar is provided with adjusting arms T^2 T^2 rigidly attached to the ends of said bars inside of the brackets and extending outwardly from the bars. The brackets T^1 are extended outwardly and are provided at their outer ends beneath the outer ends of the levers with laterally extending lugs t^1 located beneath the outer ends of the said arms T^2 . (Figs. 21 and 22). Secured in each of said lugs t^1 and rising therefrom is a screw-threaded adjusting bolt T^3 which passes through a slot in the outer end of the arm T^2 and is provided with nuts t^2 t^3 located below and above said arm. The upper and lower surfaces of said arm T^2 in the part thereof engaged by the nuts t^2 t^3 are convexly rounded, so as to afford suitable bearing surfaces for the nuts in all positions to which said arm is adjusted.

In the case of the scraper for the upper roll, the ends of the bar U thereof are likewise provided with cylindric parts or journals which engage bearing apertures formed in brackets U^1 U^1 secured by bolts to the top surfaces of the supporting arms E E^1 . To the ends of said bar U are rigidly attached adjusting arms U^2 that extend outwardly from the bar. As more clearly shown in the detail views, Figs 23 and 24, each bracket U^1 is provided at its outer end with a laterally projecting lug u^1 in which is secured an upright screw-threaded adjusting bolt U^3 . Said bolt U^3 extends upwardly through a slot in the outer end of the arm U^2 and is provided with two adjusting nuts u^2 and u^3 , located one below and the other above the arm U^2 , which latter is rounded or made convex on its upper and lower surfaces, in its part engaged by the said nuts, in the same manner as hereinbefore described in connection with the arms of the lower scraper.

The scraping blades t and u will be made of thin or elastic metal, so that their edges in contact with the rolls, will be adapted to act or press yieldingly on the surfaces of the rolls. The said blades may be secured by any suitable means to the supporting bars T and U , as, for instance, by screws, as shown in the drawings.

The machine illustrated in the drawings is provided with a top guide roll V extending longitudinally above the upper roll D and mounted at its ends in brackets V^1 V^1 which are attached to and rise from the arms E E^1 . Said machine illustrated is designed especially for treating or coating a continuous web of paper as it is delivered from the paper making machine, and the top guide roll V is used to support the web when the coating machine is not in operation, so that the web may, at such time, be carried past the coating machine without being coated and with-

out interfering with the operation of the paper making machine.

We claim as our invention:—

1. A paper coating machine comprising a machine frame, two opposing rolls, one located above the other, the lower roll being mounted in bearings on the machine frame, horizontally arranged supporting arms pivoted to the machine frame and provided with bearings for said upper roll, the machine frame and said supporting arms being provided with contacting surfaces adapted to limit the approach of the upper to the lower roll. 5
2. A paper coating machine comprising a machine frame, two opposing rolls, one located above the other, the lower roll being mounted in bearings on the machine frame, horizontally arranged supporting arms pivoted to the machine frame and provided with bearings for said upper roll, and a reservoir for supplying coating material to the upper roll mounted on said arms. 10
3. A paper coating machine comprising a machine frame, two opposing rolls, one located above the other, the lower roll being mounted in bearings on the machine frame, horizontally arranged supporting arms pivoted to the machine frame and provided with bearings for said upper roll, a receptacle for coating liquid located on the machine frame below the lower roll, and a reservoir for supplying coating liquid to the upper roll mounted on the said supporting arms. 15
4. A paper coating machine comprising a machine frame, two opposing rolls, one located above the other, the lower roll being mounted on bearings on the machine frame, horizontally arranged supporting arms pivoted to the machine frame and provided with bearings for the upper roll, a receptacle for coating liquid located below the lower roll, a feed-regulating roll mounted on the machine frame and bearing against the upwardly moving side of the lower roll, and positively acting means for adjusting said feed-regulating roll relatively to the said lower roll. 20
5. A paper coating machine comprising a machine frame, two opposing rolls, one located above the other, the lower roll being mounted on bearings on the machine frame, horizontally arranged supporting arms pivoted to the machine frame and provided with bearings for said upper roll, a receptacle for coating liquid located below the lower roll, a cleaning scraper for the upper roll mounted on said arms at the upwardly moving side of said upper roll, and a cleaning scraper for the lower roll mounted on the machine frame at the downwardly moving side of said lower roll. 25
6. A paper coating machine comprising a machine frame, two opposing rolls, one located above the other, the lower roll being mounted in bearings on the machine frame, horizontally arranged supporting arms pivoted to the machine frame and provided with bearings for said upper roll, the lower roll being mounted in bearings on the machine frame, horizontally arranged supporting arms pivoted to the machine frame, actuating means operating simultaneously on both arms for lifting at once both ends of said upper roll, said actuating means acting downwardly on said arms at points exterior to the pivots thereof, and adjustable stops on the machine frame for limiting the approach of the upper toward the lower roll. 30
7. In a paper coating machine, a machine frame, two opposing rolls, one located above the other, the lower roll being mounted in bearings on the machine frame, horizontally arranged supporting arms for the upper roll pivoted to the machine frame, and adjusting means interposed between the said bearings for the lower roll and said arms for regulating the distance apart of the said rolls. 35
8. In a paper coating machine, a machine frame, two opposing rolls, one located above the other, the lower roll being mounted in stationary bearings on the machine frame, movable bearings for the upper roll and horizontally sliding wedge blocks interposed between the bearings of the lower and upper rolls to regulate the distance apart of said rolls. 40
9. A paper coating machine comprising a machine frame, two opposing rolls, one located above the other, the lower roll being mounted in stationary bearings on the machine frame, horizontally arranged supporting arms for the upper roll, pivoted to the machine frame, and horizontally movable wedge blocks interposed between the bearings of the lower roll and said arms for regulating the distance apart of said rolls. 45
10. In a paper coating machine, a machine frame, two opposing rolls, one located above the other, the lower roll being mounted in bearings on the machine frame, horizontally arranged supporting arms pivoted to the machine frame and provided with bearings for said upper roll, means interposed between said arms and adjacent parts of the machine frame for adjustably limiting the descent of the upper roll, and weighted levers pivoted to the machine frame and connected with said supporting arms to hold the upper roll from rising. 50
11. A paper coating machine comprising a machine frame, two opposing rolls, one located above the other, the lower roll being mounted in bearings on the machine frame, horizontally arranged supporting arms pivoted to the machine frame and provided with bearings for said upper roll, actuating means operating simultaneously on both of said supporting arms for lifting the upper roll, adjustable stops on the machine frame for 55

- limiting the approach of the upper toward the lower roll, two horizontally arranged, parallel levers pivoted one above the other to the ends of the machine frame below each of 5 said supporting arms, the lower one of said levers being provided with a weight, rods connecting said levers with each other, and connecting rods pivotally connected at their ends to said arms and to the uppermost of 10 said parallel levers.
12. In a paper coating machine, a machine frame, two opposing rolls, one located above the other, the lower roll being mounted in bearings on the machine frame, horizontally arranged supporting arms pivoted to the machine frame and provided with bearings for 15 said upper roll, weighted levers mounted on the machine frame and connected with the said arms, to hold the upper roll from rising, and means connected with the outer ends of 20 said levers for depressing the same and lifting the upper roll against the action of said weighted levers.
13. The combination of a machine frame, opposing upper and lower rolls, horizontally arranged supporting arms pivoted to the machine frame and provided with bearings for the upper roll, a reservoir for supplying coating material to the upper roll provided at its 25 ends with longitudinally extending arms attached to said supporting arms, a rigid bar attached at its ends to said supporting arms and extending outside of and parallel with said reservoir, and adjusting screws engaged 30 with said bar and with the reservoir for adjusting the bottom wall of said reservoir toward and from the adjacent surface of the said upper roll.
14. The combination of a machine frame, opposing upper and lower rolls, horizontally arranged supporting arms for the upper roll pivoted between their ends to the machine frame, a horizontal rock-shaft mounted upon 40 the machine frame and provided with eccen- trics, rods engaged with said eccentrics and with the outer ends of said supporting arms, and means for turning the said rock-shaft.
15. The combination of a machine frame, opposing upper and lower rolls, horizontally arranged supporting arms pivoted between 45 their ends to the machine frame for the upper roll, a horizontal rock-shaft mounted upon the machine frame and provided with eccen- trics, rods engaged with said eccentrics and 55 with the outer ends of said supporting arms, and a crank-arm attached to said rock-shaft for turning the same.
16. The combination of a machine frame, opposing upper and lower rolls, horizontally arranged supporting arms for the upper roll pivoted between their ends to the machine frame, a horizontal rock-shaft provided with 60 eccentrics, rods engaged with said eccen- trics and with the outer ends of said support- ing arms, means for turning the said rock- 65 shaft and means for locking the said rock- shaft from turning.
17. The combination of a machine frame, opposing upper and lower rolls, horizontally arranged supporting arms for the upper roll pivoted between their ends to the machine frame, a horizontal rock-shaft mounted upon 70 the machine frame and provided with eccentrics, rods engaged with said eccentrics and with the outer ends of said supporting arms, and means 75 for locking the said rock-shaft from turning, embracing a notched wheel on the rock-shaft and a sliding detent adapted to engage said wheel.
18. The combination of a machine frame, opposing upper and lower rolls, horizontally arranged supporting arms for the upper roll, a horizontal rock-shaft mounted upon the machine frame and provided with eccentrics, rods engaged with said eccentrics and with 80 the said supporting arms, and means for locking the said rock-shaft from turning, embrac- 85 ing a notched wheel on the rock-shaft, a sliding detent adapted to engage said wheel, a spring applied to throw the said detent into 90 engagement with the notched wheel, and a foot lever connected with said detent for releasing it from the notched wheel.
19. The combination of a machine frame, opposing upper and lower rolls, horizontally arranged supporting arms for the upper roll, pivoted between their ends to the machine frame, a horizontal rock-shaft provided with 95 two eccentrics, rods connected at their upper ends with the outer ends of said supporting 100 arms, bearing plates carried by the rods, in contact with the lower surface of said eccen- trics, and means for adjusting said plates vertically upon the rods.
20. The combination of a machine frame, opposing upper and lower rolls, horizontally arranged supporting arms for the upper roll, pivoted between their ends to the machine frame, a horizontal rock-shaft provided with 105 two eccentrics, rods connected at their upper ends with the outer ends of said supporting 110 arms, said rods being provided at their lower ends with yoke pieces having depending arms which extend at opposite sides of the rock-shaft and are provided with laterally 115 extending lugs, and bearing plates seated on said lugs and engaging the lower surfaces of said eccentrics.
21. The combination of a machine frame, opposing upper and lower rolls, horizontally arranged supporting arms for the upper roll, pivoted between their ends to the machine frame, a horizontal rock-shaft provided with 120 two eccentrics, rods connected at their upper ends with the outer ends of said supporting 125 arms and provided at their lower ends with yoke pieces having laterally projecting lugs, bearing plates in contact with the lower sur-

faces of said eccentrics, and set-screws inserted through the said lugs and bearing upwardly on the ends of said bearing plates.

22. The combination of a machine frame, 5 opposing upper and lower rolls, horizontally arranged supporting arms for the upper roll, pivoted to the machine frame, bearings for the lower roll mounted on the machine frame, horizontally movable wedge blocks 10 interposed between said arms and the said bearings for the lower roll, and adjusting screws for said wedge blocks having operative connection with the latter and with one of the parts engaged by the wedge block.
- 15 23. The combination with a rotative roll for applying coating material, of a scraper, adjusting arms connected with and giving adjusting movement to the scraper, screw-threaded adjusting bolts rigidly attached to 20 the machine frame, and nuts applied to said bolts and adapted to bear against opposite sides of the adjusting arms.

24. The combination with a rotative roll for applying coating material, of a scraper, 25 adjusting arms connected with and giving adjusting movement to the scraper, screw-threaded bolts rigidly attached to the machine frame, nuts applied to said bolts on opposite sides of said adjusting arms, said 30 adjusting arms being provided with opposite convex surfaces for engagement with said nuts.

25. The combination with a rotative roll for applying coating material, of a scraper, 35 adjusting arms connected with and adapted to give adjusting movement to the scraper, screw-threaded bolts rigidly attached to the machine frame, and nuts applied to said bolts and adapted to bear against opposite 40 sides of said adjusting arms, said arms being provided with holes for the passage of the said bolts and with opposite, convex surfaces for engagement with the nuts.

26. The combination of a machine frame, 45 opposing upper and lower rolls mounted thereon, a receptacle for coating material located beneath the lower roll, a feed regulating roll located at the upwardly moving side of the lower roll, and means for adjustably 50 supporting said roll embracing angular supporting levers pivoted to the machine frame and having upright arms provided with bearings for said feed regulating roll, and adjusting arms rigid with said upright arms 55 and adjusting means connecting the said adjusting arms and having bearing on parts rigid with said machine frame.

27. The combination of a machine frame, 60 opposing upper and lower rolls mounted thereon, a receptacle for coating material located beneath the lower roll, a feed regulating roll located at the upwardly moving side of the lower roll, and means for adjust-

ably supporting said roll embracing angular supporting levers pivoted to the machine 65 frame and having upright arms provided with bearings for said feed regulating roll, and adjusting arms rigid with the upright arms, and adjusting means connecting the said adjusting arms with the machine frame, embracing screw-threaded bolts attached to the machine frame and nuts applied to said bolts at opposite sides of the said adjusting arms.

28. The combination of a machine frame, opposing upper and lower rolls, a receptacle 75 for coating material located beneath the lower roll, a feed regulating roll located at the upwardly moving side of said lower roll, angular supporting levers for said roll having upright arms provided with bearings for 80 said feed regulating roll, and adjusting arms rigid with said upright arms, brackets bolted to the machine frame to which said supporting levers are pivoted, said brackets being provided with laterally extending lugs, screw- 85 threaded bolts secured to said lugs, and nuts applied to said bolts at opposite sides of the said adjusting arms, said arms being provided with holes for the passage of said bolts.

29. The combination with a rotative roll 90 for applying coating material, of a cleaning scraper consisting of a supporting bar and a scraping blade attached to the bar and having angular relation to the surface of the roll, said bar being mounted to turn in bearings on the machine frame, means for effecting angular adjustment of said bar, embracing adjusting arms rigidly attached to the ends of the bar, screw-threaded bolts on the machine frame, and nuts applied to said 95 bolts and adapted to bear against opposite sides of said adjusting arms.

30. The combination with a machine frame and a rotative roller for applying coating material, of a cleaning scraper comprising a supporting bar and a scraping blade attached thereto and bearing at its edge against the surface of the roll at an angle thereto, brackets upon the machine frame provided with bearings for the ends 100 of said supporting bar, adjusting arms rigidly attached to the ends of said supporting bar adjacent to said brackets, screw-threaded adjusting bolts affixed to said brackets, and nuts applied to said bolts and engaging opposite ends of said adjusting arms.

31. The combination with a machine frame, of a rotative roller for applying coating material, a cleaning scraper having a scraping blade, the edge of which bears 110 against the surface of said roll at an angle thereto, brackets on the machine frame provided with bearings for the ends of said scraper, said brackets having laterally projecting lugs, adjusting arms rigidly attached 115 to the ends of the scraper adjacent to said

bracket, screw-threaded adjusting bolts secured to said lugs on the brackets, said arms being provided with slots for the passage of said bolts, and nuts applied to said bolts at 5 the opposite sides of said arms.

In testimony, that we claim the foregoing as our invention we affix our signatures in

the presence of two witnesses, this 31st day of October A. D. 1906.

FRANK B. DAVIDSON.
WILLIAM GORGES.
